UNITED STATES PATENT OFFICE.

JOSEPH L. WRIGHT, OF WASHINGTON, DISTRICT OF COLUMBIA, ASSIGNEE, BY MESNE ASSIGNMENTS, TO FREDERIC C. STEVENS, OF ATTICA, NEW YORK.

TELEPHONE-EXCHANGE SYSTEM.

1,128,646.

Specification of Letters Patent. Patented Feb. 16, 1915.

Application filed March 8, 1912. Serial No. 632,337.

To all whom it may concern:

Be it known that I, JOSEPH L. WRIGHT, a citizen of the United States, and resident of Washington, District of Columbia, have 5 invented certain new and useful Improvements in Telephone-Exchange Systems, of which the following is a specification.

My invention relates to telephone exchange systems, particularly to the signaling circuits associated with link or cord-circuits for effecting connections between telephone lines.

The object of my invention is to provide improved means in controlling the signaling circuit during the establishment and completion of a connection.

I have shown my invention as applied to a cord-circuit in connection with a manual switch-board. The circuit for controlling the signaling is established when the answering plug of the cord-circuit is placed in the calling line jack and the calling plug placed in the line jack of the called line and the circuit of the calling line closed. The 25 control exercised in this manner prevents the operator from signaling subscribers, unless the calling subscriber has his line circuit closed when the circuit is finally established. After the circuit is established the 30 ringing is under control of the operator and the called subscriber. The operator can disable the signaling circuit by withdrawing the plugs, and the called subscriber can disable the same by removing his receiver 35 during a non-signaling interval.

My invention is illustrated in the accompanying drawing, wherein the subscriber's station at A is equipped with apparatus usual in common battery systems. The line 40 wires from this station terminate in the jack J and also through the line relay E and ground through the contacts of the cut-off relay D. The answering plug P and the calling plug P¹ of the cord-circuit are joined together by the conductors indicated in 45 heavy lines for conversational purposes, and these conductors are separated by the condensers 30 and 40. The relay H and retardation coil I are connected to the tip and sleeve conductors of the answering plug and furnish talking current for the calling subscriber. The relay N and the retardation coil S are connected to the tip and sleeve conductors of the calling plug and furnish 50 talking current to the called subscriber. The

relay K is placed in series with the cut-off relay D when the plug is placed in the jack. The relay D disconnects the relay E and ground from the line, while the relay K closes the circuit of the lamp G through 60 the contacts of relay H. The relay K also maintains the locking circuit of the relay M until the called party answers, or until the plugs are withdrawn from the jacks. The relay L is placed in series with the cut-off 65 relay of the called line when the plug is placed in the jack, and when energized closes the circuit of the supervisory lamp T through the contacts of the relay N. The relay L, together with the relay M jointly 70 control the circuit of relay R. This latter relay when energized, connects generator current to the called line and also places the relay O under control of the commutator Y. This commutator acting intermittently, opens and closes the circuit of the 75 relay O. These commutators U and Y may be common to a group of links. The condenser X is individual to a link circuit and is interposed to prevent interference between the tip relays of various other link 80 circuits where the commutator U is made common to a group. When the relay O is energized, the tip relay N and retardation coil S are disconnected and placed beyond 85 control of the called subscriber. After the relay R is energized, generator current from W is connected through the commutator U in series with the condenser X, this relay remaining continuously energized until the 90 control circuit is disabled. The commutators Y and U are arranged so that the relay O is energized, before the generator is connected through the commutator U, and also maintains the circuit of the relay O 95 until the generator current is disconnected by the commutator U. The called subscriber upon answering, when the relay O is deenergized, closes the circuit of the relay N, disconnects relay M, which in turn disconnects relay R. This latter relay then disconnects relay O and prevents any further action of the generator current in this 100 particular connection.

Having described the circuits in a general 105 way, I will now point out the detailed operation in effecting a connection from the calling subscriber A to the called subscriber C. Subscriber A removing his receiver closes the circuit of the relay E, which in 110

turn lights the lamp F. The operator noticing this signal places the plug P in the jack J, thereby energizing relays D and K in series. The operation of relay D disconnects relay E, which in turn extinguishes the lamp F. The relays K and H operating, the latter through the subscriber's station closes the circuit of the relay M as follows: ground, contacts of K, 15, contacts of H, 22, contacts of L, 16, M, 17 to battery B through the contacts of N. The operator throws forward her listening key in the regular manner and upon getting the proper number from the calling subscriber, places the plug P¹ into the jack J¹, thereby placing relays L and D¹ in series. The operation of relay L closes the circuit of relay R as follows: battery B, contacts of L, 7, contacts of M, relay R to ground. The operation of relay R connects commutator Y to the relay O as follows: ground, Y, 13, contacts of R, 12, O, battery B. The operation of this relay disconnects the relay N and the coil S. Immediately after the operation of relay O, generator W is connected to the called line as follows: ground, W, U, X, contacts of R, 11, 101, ringer and condenser at C, 102, 8, 21, contacts of R to ground. This generator current causes the bell at C to ring so long as the generator circuit is completed through the commutator U. After this generator current is cut-off by the commutator, the circuit of the relay O is opened by the commutator Y¹, allowing the relay N and the coil S to become connected to the tip and sleeve conductors. The subscriber at C answering at this time closes the circuit of relay N. The action of this relay extinguishes the lamp T, notifying the operator that the called party has answered. This relay also closes the tip conductor between the calling and answering plugs and also disconnects relay M. Relay M becoming disconnected releases relay R, which in turn disconnects relay O from the commutator Y. The calling and called subscribers are now connected and the signaling circuit disabled. When the subscribers are through talking, the lamps G and T are lighted and the operator, upon getting this disconnect signal, removes both plugs from the jacks. It will be noted that the relay M can only be energized when relays H and K are operated, the relay H closes the starting circuit of the relay M, while the relay K maintains the circuit when it is once established. Controlling the circuits in this manner prevents the operator from ringing or calling any subscriber unless a call actually originates and the connection put through in the regular manner. In order to enable the operator to ring at any other time, the wire 22 instead of leading to a contact in relay H could be connected directly to wire 15 leading to a contact in relay K. The circuit ar-

ranged in this manner would give the operator control of the ringing circuit by simply placing an answering plug into the jack of a non-busy line which would energize the relay M without any action of the relay H. For emergency, the operator could be provided with a button which would connect ground directly to the wire 22. 70

I have shown my invention as applied to a cord-circuit in connection with a manual exchange, but it could readily be applied to other forms of link circuits without departing from the spirit of the invention. 75

Having thus described my invention, what I desire to secure by Letters Patent is: 80

1. In a telephone exchange system, subscribers' lines, a link circuit for interconnecting them, a ringing relay arranged to be continuously energized to apply ringing current to the calling end of said link through its own contacts, an auxiliary relay arranged when actuated to sever the link circuit, an intermittent circuit closer controlling the circuit of said auxiliary relay, and means controlled by the called subscriber for disabling both the ringing and auxiliary relays when a call is answered. 90

2. In a telephone exchange system, subscribers' lines, a link circuit for interconnecting them, a ringing relay arranged to be continuously energized to apply ringing current to the calling end of said link through its own contacts, a source of ringing current together with means connecting the same intermittently to the contacts of said ringing relay, an auxiliary relay arranged when actuated to sever the link circuit, an intermittent circuit closer controlling the circuit of said auxiliary relay in synchronism with the application of ringing current to the contacts of the ringing relay, and means controlled by the called subscriber for disabling both the ringing and auxiliary relays when a call is answered. 100 105

3. In a telephone exchange system, a calling and called subscriber's line, a link circuit having switching terminals for interconnecting them, a continuously energized relay for connecting ringing current with the called line, means under control of the calling subscriber at the initiation of a connection, to primarily control the action of said relay, and means controlled in the establishment of the connection to complete the action of said relay and to remove the same from the control of the calling subscriber. 110 115

4. In a telephone exchange system, a calling and called subscriber's line, a link circuit for interconnecting them, a ringing relay and generator therefor, together with a control circuit for said relay, a locking relay in said circuit, means under control of the calling subscriber for actuating said locking relay to maintain the continuous 120 125 130

action of said ringing relay, and means under control of the called subscriber for disabling said relays.

5. In a telephone exchange system, a calling and a called subscriber's line, a link circuit for interconnecting them, a ringing generator, together with connecting means and a control circuit therefor, a relay in said circuit initially controlled by the calling 10 subscriber for maintaining the continuous

actuation of the connecting means; means at intervals under control of the called subscriber to disable said connecting means.

In testimony whereof I affix my signature in presence of two witnesses.

JOSEPH L. WRIGHT.
